ABSTRACT: An assembly of holders for the knives of pressure or squeeze-acting roller cutting machines for longitudinally cutting webs, particularly of a strong material such as cellulose and cotton wool, includes individual flat knife-holder assemblies having fluid pressure operated movable piston elements which are coupled to the knife through individual mounting elements having forked legs. The forked leg mounting elements are arranged to slide between casing plates. The assembly of knives is such that alternate knife holders or extensions thereof extend between the plates of the next adjacent knife assemblies. In this manner, the pressure casings for the reciprocal piston member which is connected to the forked knife mounting elements are alternately arranged at different mounting levels so that the whole assembly may be compressed within a small space to facilitate the close spacing of the knife elements.

KNIFE HOLDER ASSEMBLY

SUMMARY OF THE INVENTION

This invention relates, in general, to the construction of holders for cutting knives and in particular to a new and useful assembly of holders for pressure-cutting knives of roller cutting machines in which the knives are arranged very closely together.

The present invention particularly relates to a knife holder assembly which includes individual knives which may be pressed into cooperative cutting positions against a counter roller through the action of a piston movable in a pressure cylinder. Such knives are used principally for dividing webs longitudinally, particularly for cutting strong material such as cellulose, cotton wool and the like. In the type of knife holders with which the present invention is concerned, a piston for each holder or knife mounting element is coupled with a forked flat mounting plate or bearing fork. The legs of the forked mounting plate fit snugly or flush within guide grooves defined between laterally spaced casing plates. A pressure casing for the actuating piston which is connected to the fork plate is constructed as a flat boxlike structure arranged with its sidewalls extending longitudinally and parallel above the casing plates on each side of the forked mounting element. Knife holders of this type are known, as indicated in German Pat. No. 1,072,878 and they have the advantage that they are carries simple in construction and they may be operated exactly and rapidly. This is true because the relative cutting width distances have been set on the knife beam which carries the holders of the individual knives so that all of the knives can be operated at the same time and with the same force against a common pressure roller or counter roller. Pressure force is set by connecting the individual pressure casings for each knife through a common pressure source through suitable valve means.

The known construction of the knife assembly as described above permits a relatively large effective piston cross section with a relatively small axial dimension so that a large pressure cutting force can be transmitted through the individual mounting forks to the knives. Because the mounting forks for the individual knives are guided with a tight fit between the side plates of each assembly, it is capable of transmitting a very large operating knife force.

With the known knife assemblies, narrow strips can be cut away from the web without interfering with the operation of the pressure transmitting means to the individual fork mounting elements. However, for some purposes, it is desirable to cut still smaller strip widths than has been possible with the known machines. In order to be able to do so, the knife holders had to be arranged so that they are offset in a peripheral direction and in the axial direction of the pressure roller. This required the fitting of the cutting machine with at least two knife beams, or the pressure medium actuation had to be replaced by blade-shaped springs which had to be adjusted individually at each individual knife holder by means of a tension screw. In addition, in order to accomplish the adjusting movement, the knife beam had to be rotatable or tiltable at the machine.

In accordance with the present invention, a knife assembly is provided which is operated by a pressure medium but which is, nevertheless, capable of cutting extremely narrow widths and which permits the mounting of the knives very closely together. This is accomplished by arranging alternate pressure housings or casings at one level or spacing and the other pressure housings or casings are offset, i.e., they are at a separate level, for example, a higher level. The pistons of the pressure casings at the lower level are connected directly to the forked members mounting the individual knives while the pistons of the pressure casings which are at a higher level are connected through extensions to the forked elements mounting the knives of these holders. The guide walls which are arranged on each side of the forked knife holders are arranged together in a grooving or stack below the pressure holders at the lower

level. The arrangement is such that the respective extended and unextended holders may be carried on single knife beams located axially one behind the other or one above the other as the case may be. The construction permits a very small cutting width setting and the support walls for the forked knife holders may be arranged flush together in a compact stack which provides a very rigid supporting structure. Thus, the invention makes it possible to provide an extremely small built-in axial dimension of the casing plates to produce the same technical force or load in a much smaller width.

With extreme utilization of the possibility suggested by the invention to decrease the cut width, it may occur that the pressure casing at its free rim will be somewhat spread apart by the action of the pressure medium to cause a lessening of the sealing of the collar at the pressure casing. This is possible because the pressure casing of the outermost individual knife assemblies is not supported on the next adjacent member. In order to overcome this disadvantage, the invention provides means for tensioning a screw between the longitudinal walls of the pressure casings above the free rim of the exposed pressure casings. The tensioning screw is advantageously mounted so that it may be moved with play in a longitudinal hole at the end of the piston which is on the driving side. With such an arrangement, the inner walls of the pressure casing can be arranged parallel and can be adjusted within wide tolerance ranges.

Accordingly, it is an object of the invention to provide an improved knife assembly which includes a plurality of individual knife holder assemblies comprising side plates defining grooves therebetween in which are slidably individual knife mounting elements. The knife mounting elements are connected to pistons which are movable in fluid pressure housings or casings to apply the knife pressure to a counter roller. Alternate fluid pressure housings are offset either laterally or vertically from the others and the individual knife mounting members are connected to the respective pistons in the offset housings of greater length by extension plates which extend between the housings of the others of the individual knife assemblies.

A further object of the invention is to provide a mounting arrangement particularly for pressure type or compression knives capable of cutting webs longitudinally over pressure rollers wherein the housings for the mounting elements for the knife are arranged in a flat stack permitting close lateral spacing of the knives and which advantageously includes means for adjusting the seal of a fluid cylinder housing bearing a piston member which is adapted to be connected to the individual knife mounting elements for applying an operating pressure to the knives.

A further object of the invention is to provide an assembly of hydraulically or pneumatically operable holders for rotating squeezing knives or pressure knives which cooperate with a pressure roller and which is simple in design, rugged in construction and economical to manufacture.

BRIEF DESCRIPTION OF THE DRAWINGS

In the Drawings:

FIG. 1 is a partial perspective and front elevational view of a knife assembly adjusted to the smallest cutting width and constructed in accordance with the invention;

FIG. 2 is a partial end elevational view of the right-hand portion of the knife assembly indicated in FIG. 1;

FIG. 3 is a radial section through a longer knife holder element of the knife assembly indicated in FIG. 1;

FIG. 4 is an elevational view similar to FIG. 2 of the longer knife holder type indicated in FIG. 1;

FIG. 5 is a radial section similar to FIG. 3 but of the shorter knife holder type; and

FIG. 6 is a side view of the shorter knife holder type indicated in FIG. 5.

GENERAL DESCRIPTION OF THE PREFERRED EMBODIMENTS

Referring to the drawing, in particular, the invention embodied therein comprises the construction and arrangement of an overall assembly generally designated 60 of individual cutting knife subassemblies generally designated 62 and 64.

In accordance with the invention, each of the subassemblies 62 and 64 includes a rotary pressure-cut or squeeze-knife 23 having a sharpened edge 24. The knife 23 is mounted in clamping slots 25 at the ends of knife mounting members or holding plates 26 which have forked legs or ends 26a which define the slot 25 for receiving the hub portion 10 of the knives 23. The hubs 10 are supported on roller bearings 16.

Each of the knife mounting members 26 is accommodated within inner guides or grooves 27 defined between laterally spaced casing plates. The mounting plates 26 are arranged with a snug or flush fit within the grooves 27 so that the hub end faces of the knife 23 are supported in a play free manner against "edging" from the inner surfaces of these plates. The mounting plates 26 with the knives 23 are moved in operative pressure engagement against a web (not shown) which is fed over a counter roller or pressure roller 31. The knives are operatively engaged in pressure-cutting contact with a web by a fluid-pressure operated piston 2 which is connected to the outer ends of each plate 26. The piston 2 is slideable in a pressure casing or housing 1 and the squeeze-knife 23 together with the mounting member 26 carried by the piston 2 can move axially relative to the box-shaped pressure casing 1. The displacement of the piston 2 within its housing 1 is accomplished by applying a fluid pressure force to the piston collar 3 to move the knife 23 in a cutting direction. Biasing means such as springs 15 act to move the knives backwardly in a counter or retracting direction. The springs 15 are arranged in holes of lining pieces 6 (FIG. 4) in the plates 4 and 5.

Each pressure casing 1 has a larger axial dimension or width than the plates 4 and 5. Each second pressure casing 1 in a row as indicated in FIG. 1 has its end flush with the outer ends of the plates 4 and 5 as indicated in FIGS. 5 and 6, when the knives are in a cutting position. Each alternate plate assembly 62 includes an exterior extension plate 28, 7 on respective sides extending between the pressure casing 1 and the plates 4 and 5 and an extension member 20 extending centrally between the piston 2 and the associated knife mounting plate 26. Securing means such as bolts 8 hold the assemblies together. In this manner, even when the smallest cutting width is to be cut, the knife holders may be assembled together with the subassemblies 62 and 64 arranged alternately and boxed together to form an overall relatively strong structure as seen in FIG. 1. Securing means such as bolts 8 hold the assembly of plates 4 and 5 and pressure casings 1 together so that it may be mounted as a unit on a holder beam 30.

In order to insure that the pressure casing 1 is not spread apart at its sealing edge by the action of the pressure medium, the longitudinal rims or edges of the pressure casing are connected together by an adjustable tension screw 22. The tension screw 22 is arranged with play in a longitudinal slot 29 at a location to permit movement of the connection of the piston 2 to the extension plate 20 at the location 19 as shown in FIG. 3.

The setting of the holder assembly 60 on the holder beam 30 may be adjusted by a prism mechanism which includes an adjusting screw 12 threadably mounted on an extension so that it may bear against a prism or stop 13 which is carried in a

fixed end position on a pivot 17 so as to extend angularly below the threaded member 12.

I claim:

1. An assembly of holders for rotating squeeze-knives which are adapted to cooperate with a pressure roller for the purpose of longitudinally cutting webs, particularly of a strong material such as cellulose and cotton wool, comprising a plurality of knife holder subassemblies each including side plates adapted to be arranged closely together with the plates of adjacent subassemblies in touching contact for the purpose of cutting very narrow widths of web material, said side plates of each subassembly defining interior knife mounting plate guides, a knife mounting plate mounted for movement in each of said guides, a knife carried by each of said mounting plates and projecting beyond said side plates for engagement over a web positioned on the pressure roller, a fluid pressure casing for each subassembly, a piston movable in said fluid pressure casing under the force of fluid actuating pressure and connected to said knife mounting plate for moving said mounting plate with said knife, said subassemblies being arranged with alternate ones of said pressure casings being in a row which is offset from the row of the remaining pressure casings, the connection between the pistons of said offset row of pressure casings to said mounting plate means extending between the pressure casings of the remaining rows, and securing means for securing said side plates and said fluid pressure casings together in an assembly which may be adjustably positioned in respect to the pressure roller.
2. An assembly according to claim 1, wherein said connection between the pistons of said offset row to said mounting plate includes an extension member connected between said plate and said piston.
3. An assembly according to claim 1, wherein said mounting plate includes a forked end defining a groove, said knife being rotatably mounted in said groove.
4. An assembly according to claim 1, wherein said side plates include a plate on each side of said mounting plate.
5. An assembly of holders for rotating squeeze-knives which are adapted to cooperate with a pressure roller for the purpose of longitudinally cutting webs, particularly of a strong material such as cellulose and cotton wool, comprising a plurality of knife-holder subassemblies each including side plates adapted to be arranged closely together with the plates of adjacent subassemblies in touching contact for the purpose of cutting very narrow widths of web material, said side plates of each subassembly defining interior knife mounting plate guides, a knife mounting plate mounted for movement in each of said guides, a knife carried by each of said mounting plates and projecting beyond said side plates for engagement over a web positioned on the pressure roller, a fluid pressure casing for each subassembly, a piston movable in said fluid pressure casing under the force of fluid actuating pressure and connected to said knife mounting plate for moving said mounting plate with said knife, said subassemblies being arranged with alternate ones of said pressure casings being in a row which is offset from the row of the remaining pressure casings, the connection between the pistons of said offset row of pressure casings to said mounting plate means extending between the pressure casings of the remaining row, said pressure casing including sidewalls, and at least one tensioning screw extending between said sidewalls for holding said sidewalls together, said connection from said piston to said knife mounting plates including a longitudinally extending slot accommodating said tensioning screw.
